VULCANIZING APPARATUS

William C. Wright, Daniel G. Rowe, Jr., and Elmer Ford Roberts, Hickory, N.C.

Application January 2, 1946; Serial No. 638,602

2 Claims. (Cl. 18—6)

1
This invention relates to a vulcanizing press and more especially to an apparatus wherein a plurality of suitable molds can be placed, each mold having a wheel therein with a solid rubber tire therearound which is to be vulcanized onto the wheel which is usually metallic or wood.

It is an object of this invention to provide a vulcanizing press having a chamber surrounded by a steam jacket and means whereby live steam may be passed through the chamber and also live steam can be passed through the steam jacket surrounding the chamber or, if desired, only live steam may be passed through the jacket and no steam admitted to the chamber, or vice versa, together with means whereby one end of the compartment is closed by fluid pressure means such as pneumatic means. There is also means in the form of a plunger which can be moved into the chamber to exert the proper amount of pressure on the molds and the wheels with tires thereon which are contained within the mold.

It is another object of this invention to provide a vulcanizing press having inner and outer cylindrical members forming a steam chamber between the inner and outer cylindrical members and having means whereby steam may be passed through the inner cylindrical member in which a plurality of members being vulcanized are disposed and having means whereby live steam can also be passed through the space between the inner and outer cylindrical members for heating the interior of the inner cylindrical member together with fluid pressure means for closing one end of the inner cylindrical member and the other end of the cylindrical member having a piston therein with fluid pressure means for pressing the piston toward the other end of the cylindrical member to thereby exert pressure on objects being vulcanized within the inner cylindrical member.

Some of the objects of the invention having been stated, other objects will appear as the description proceeds when taken in connection with the accompanying drawings, in which:

Figure 1 is an elevation of the apparatus with portions thereof broken away;

Figure 2 is a vertical sectional view taken through the upper control valve for controlling pneumatic pressure to the piston chambers;

Figure 3 is a view similar to Figure 2, but preferably being taken through the lower valve in Figure 1 for controlling pneumatic pressure to the lower piston chamber;

Figure 4 is a vertical sectional view through the apparatus with portions thereof broken away, and taken along the line 4—4 in Figure 1;

Figure 5 is a top plan view of the lowermost of the members for confining the levers for closing the upper end of the chamber, as will be presently described;

2

Figure 6 is a sectional view taken through the rim of the cap closure means for the upper end of the inner cylindrical member, with the parts which slide therein being removed;

Figure 7 is a transverse sectional view taken along the line 7—7 in Figure 1;

Figure 8 is a transverse sectional view taken along the line 8—8 in Figure 1.

Referring more specifically to the drawings, the numeral 10 indicates a base plate having a plurality of legs 11 secured thereto by any conventional means such as a clamp 12 and bolt 13. This base plate 10 has welded to the upper surface thereof, an inner cylinder 15 and an outer cylinder 16. On the upper end of these cylinders 15 and 16 there is welded an annular member 17. This member 17 has an upstanding peripheral portion 18 in the inner surface of which there is an undercut groove 20. The annular member 17 which is welded to the upper ends of cylinders 15 and 16 thus closes an annular chamber 21 between the inner cylinder 15 and the outer cylinder 16.

To the annular member 17 there is secured a plurality of braces 25 which extend upwardly and inwardly and at their upper ends are suitably secured to a member 26 which has bolted to its upper surface a flange 27 of a cylinder 30. Member 26 has a cavity 28 centrally disposed in its upper surface. The flange portion 27 of the cylinder 30 is secured to the upper surface of member 26 by means of suitable bolts 31. The upper end of cylinder 30 is closed by means of suitable bolts 34.

Slidably mounted in cylinder 30 is a piston 35 which has a piston rod 36 secured in its lower central portion which extends through a packing gland 37 centrally disposed in the base member 26. This piston rod 36 has confined on its lower end a pair of disk members 40 and 41 having therein a plurality of cavities 42, in which ball portions 43 of levers 44 are pivotally mounted. The lower end of piston rod 36 has a bore therein into which a pin 45 slidably projects, said pin being fixed centrally of a closure member 47. This closure member is adapted to fit onto a suitable gasket 48 embedded in the upper surface of annular portion 17.

The closure of lid 47 has an annular upstanding rim 50 in which a plurality of slots 51 appear and in which the free ends of levers 44 have sliding movement. These slots, as will appear, are radially disposed. The levers 44 have pins 52 mounted therein and these pins have sliding movement in horizontally disposed slots 53 cut in the upstanding annular portion 50. The free ends of levers 44 when in the position shown in Figures 1 and 4, project into the annular groove 20 on the inner surface of upstanding annular

portion 18 and thus lock the closure 47 in position with relation to the annular member 18.

Normally resting on the top of base 10 and slidably fitting within the inner cylinder 15 is a plate 60 which has secured thereto as by threading a piston rod 61 which passes through a centrally disposed hole in base member 10 and through a suitable packing gland 62. This base member 10 has a downwardly projecting boss 63 to which is secured a lower cylinder 64 by means of bolts 65 and into which the piston rod 61 projects. This piston rod has on its lower end a piston 66, and the lower end of lower cylinder 64 is closed by a suitable catch 67 secured thereto by any suitable means such as bolts 68.

Into the chamber disposed within the inner cylinder 15 there is adapted to be placed a plurality of molds comprising sections 70 and 71 into which a suitable wheel 72 is adapted to be placed, on which a rim or tire 73 of rubber is disposed, to be vulcanized onto the wheel 72. These molds, such as 70 and 71, have overlapping edges shown at 14.

The entire depth of the cylinder 15 can be filled with several of these molds of different shapes and sizes, and all can be processed at the same time after pressure is applied to same.

Means for applying pressure to the molds within the cylinder 15 and for confining the closure or lid 47 in position comprises a suitable source 80 of compressed air having leading therefrom a pipe 81 from which branch pipes 82 and 83 lead to suitable four-way valves 84 and 85.

Valve casing 84 has ports, 86, 87, 88, and 89, port 88 being an exhaust port. From port 87 a pipe 90 leads to the upper end of cylinder 30 and from port 89 a pipe 91 leads to the lower end of cylinder 30. Valve casing 84 has rotatably mounted therein a suitable core 92 having passageways A and B passing therethrough. Valve casing 85 has ports 93, 94, 95, and 96, 96 being an exhaust port.

The valve casing 85 has rotatably mounted therein a suitable core 97 having passageways C and D leading therethrough. Pipe 83 is connected to port 93 and extending from port 94 is a pipe 98 which leads to the upper end of lower cylinder 64. Port 95 has leading therefrom a pipe 99 which leads to the lower end of cylinder 64.

Means are also provided whereby steam can be admitted not only to the interior of inner cylinder 15 but also to the space between the cylinders 15 and 16. In the event that the wheels 72 should not be metallic, but of wood or other material, which would be affected by contact with live steam, then steam would be admitted only to the space 21 between inner and outer cylinders 15 and 16; but where the type of wheel is such as to permit live steam to be present in the vulcanizing chamber, then the steam can be admitted not only to the space between the inner and outer cylinders 15 and 16 but also to the interior of the inner cylinder 15 to thus hasten the vulcanizing operation as better heating will be accomplished by having steam inside the inner cylinder 15 as well as in the space surrounding the inner cylinder 15.

A suitable source of steam 100 is provided, such as a suitable generator, and leading from this is a pipe 101 which has branch pipes 102 and 103 leading therefrom. Pipe 102 penetrates the outer cylinder 16 by a steam pipe fitting and communicates with the interior of inner cylinder 15. Pipe 103 is connected to communicate with the space 21 between the inner and outer cylinders 15 and 16. These pipes 102 and 103 have suitable manually operated valves 104 and 105 therein.

In order to provide for the passage of steam through the interior of cylinder 15 and through the space 21 and to allow condensate to drain therefrom, pipe 106 leads through the base 10 and communicates with the interior of cylinder 15 while pipe 107 leads through the base 10 and communicates with the space 21 between inner and outer cylinders 15 and 16. These pipes have suitable valves 108 and 109 therein, and connect to a return line 110 which has a suitable trap 111 therein. Pipe 112 leads from this trap and may exhaust into the atmosphere or, it may lead back and join to the source of steam 100 as at 112* to provide a circulating system for the steam to be passed through the interior of cylinder 15 and the space 21 between the cylinders 15 and 16.

Method of operation

With the valve core 92 in position shown in Figure 2 and with core 97 in Figure 3 turned about 45° from the position shown in Figure 3 to cut off all ports from communication with passageways D and C, compressed air will be passed through pipe 91 to the bottom of cylinder 30 which will cause the piston 35 to be moved upwardly which will disengage the free ends of levers 44 from the circular cavity 20 and unlock the lid 47, and the lid 47 will be raised upwardly until the member 40 strikes the packing gland nut which confines the packing gland 37, and in this position, any number of molds with wheels and tires therein are packed into the inner cylinder 15. Then, core 92 will be turned counterclockwise a quarter revolution from the position shown in Figure 2 which will cause channel B to establish communication between ports 86 and 87. This will place compressed air into the upper end of the cylinder 30 and will move the parts to the position shown in Figures 1 and 4. This will lock the closure 47 in position. This air pressure will be left in "on" position, and then valve core 97 in valve 85 will be rotated a quarter revolution in a clockwise manner in Figure 3, which will cause channel C to establish communication between ports 93 and 95. This will force compressed air into the lower end of cylinder 64 and will move piston 60 upwardly to where the molds will be pressed against the lower surface of closure member 47 and the required amount of pressure will thus be exerted and this valve 85 will be left in "on" position. With the parts in this position then, steam can be admitted to the inner chamber 15 as well as to the outer chamber 21 until the vulcanizing operation has been completed. If it is not desired to admit steam to the inner cylinder 15, then steam can be admitted only to the space 21 to give the proper amount of heat for the proper length of time to the object being vulcanized.

When the operation is completed, valves 104 and 105 will be moved to closed position and then valve core 92 will be turned to the position it occupies in Figure 2 which will allow compressed air to enter the lower end of cylinder 30 and, at the same time, pipe 90 will vent through channel A to the exhaust port 88 and, thus, the piston 35 will move upwardly to disengage and finally lift the closure 47 into upmost position. In this position, the molds containing the wheels can be removed from the inner cylinder 15 and then valve core 97 can be turned to the position occupied in

Figure 3 which will force compressed air through pipe 98 and air will vent out of pipe 99 through exhaust port 96, and the piston 60 will be moved to lowered position as shown in Figure 4 ready for refilling the inner cylinder 15 with another set of molds and wheels for another vulcanizing operation.

In the drawings and specification, there has been set forth a preferred embodiment of the invention, and although specific terms are employed, they are used in a generic and descriptive sense only, and not for purposes of limitation, the scope of the invention being defined in the claims.

We claim:

1. Vulcanizing apparatus comprising a base member, inner and outer cylinders of different dimensions having their lower ends welded to the upper surface of the base member and forming an annular space therebetween, an annular member having its lower surface welded to the upper ends of the two cylinders and having a groove extending around its inside surface and having an annular recess in the lower wall of said groove, a gasket disposed in said annular recess, a plate slidably mounted in the lower portion of the inner cylinder and having a piston rod extending downwardly therefrom through the base member, a cylinder secured to the lower surface of the base member and into which the piston rod projects, a piston on the lower end of the piston rod, a closure member adapted to fit into the annular member secured on the upper ends of the two cylinders and to rest on the gasket, the closure member having a plurality of radially disposed levers slidably and pivotally mounted therein intermediate their ends, a second piston rod and means for pivotally securing the other ends of the levers to the second piston rod, a frame secured to the annular member and extending upwardly, an upper cylinder mounted on the frame and having a second piston slidably mounted therein and connected to the second piston rod projecting upwardly from the closure member, a pin secured to and rising upwardly from the closure member, and the last named piston rod having a bore therein slidably fitting over the pin, a plurality of molds being adapted to rest on the plate associated with the lower cylinder, means for admitting compressed air into the upper end of the upper cylinder to force the closure member downwardly and to force the pivoted ends of the levers downwardly to cause their free ends to slide outwardly and upwardly into the groove in the annular member, to lock the closure member in position, means for forcing compressed air into the lower end of the lower cylinder for forcing the plate associated therewith upwardly in the inner cylinder to compress the molds with suitable objects to be vulcanized therein against the closure member, means for admitting steam into the inner cylinder and other means for admitting steam into the space between the inner and outer cylinders, means for returning the steam from the lower portions of the inner cylinder and space between the inner and outer cylinders and back to the source of steam, means for forcing compressed air into the lower end of the upper cylinder and venting air from the upper end of the upper cylinder to raise the piston in the upper cylinder to withdraw the pivoted levers from the groove in the annular member and to raise the closure member, and means for

forcing compressed air into the upper end of the lower cylinder and exhausting the air from the lower end thereof to lower the plate in the lower portion of the inner cylinder.

5 2. Vulcanizing apparatus comprising an inner cylinder forming a compartment into which objects to be vulcanized can be placed, an outer cylinder of larger dimensions than the inner cylinder and providing a space therebetween, a base member to which the lower ends of the cylinders are secured, an annular member secured to the upper ends of the two cylinders, a closure member fitting into the annular member, a plurality of sliding levers mounted on the closure member, the annular member having a cavity extending around the inner surfaces thereof into which the free ends of the sliding levers are adapted to fit, a piston rod on which the inner ends of the levers are pivotally mounted, an upper cylinder disposed above and supported by the annular member into which the piston rod projects and having a piston disposed within said cylinder, means for admitting a compressed fluid to the upper end of the upper cylinder for forcing the closure member into the annular member and for forcing the inner ends of the levers downwardly to project their free ends into the groove in the annular member to thus lock the closure member in position, a plate mounted in the lower portion of the inner cylinder and on which molds containing objects to be vulcanized are adapted to rest, a piston rod extending downwardly from the plate and having a piston on its lower end, a lower cylinder surrounding the last named piston and means for admitting a compressed fluid into the lower end of the lower cylinder for forcing the plate in the lower end of the inner cylinder upwardly to force the molds against the closure member, means for admitting steam into the inner cylinder, means for admitting steam into the space between the inner and outer cylinders, means for admitting a compressed fluid to the lower end of the upper cylinder for releasing the levers from the annular member and lifting the closure member upwardly, means for forcing a compressed fluid into the upper end of the lower cylinder for lowering the plate in the inner cylinder, the means for admitting the compressed fluid into the two ends of the upper and lower cylinders comprising means for venting the compressed fluid from one end of the cylinders at the same time the compressed fluid is admitted into the other end of the upper and lower cylinders.
